(57) **CLAIM**

The ornamental design for a stabilizer for mechanical devices, as shown and described.

DESCRIPTION

FIG. 1 is a first perspective view of a stabilizer for mechanical devices showing the new design in use with a pump.

FIG. 2 is a second perspective view of the stabilizer for mechanical devices of FIG. 1 in use with the pump.

FIG. 3 is a third perspective view of the stabilizer for mechanical devices of FIG. 1 in use with the pump.

FIG. 4 is a fourth perspective view of the stabilizer for mechanical devices of FIG. 1 in use with the pump.

FIG. 5 is a rear right perspective view of the stabilizer for mechanical devices of FIG. 1 in a first configuration with the pump removed.

FIG. 6 is a rear left perspective view of the stabilizer for mechanical devices of FIG. 1 in the first configuration.

FIG. 7 is a front right perspective view of the stabilizer for mechanical devices of FIG. 1 in the first configuration.

FIG. 8 is a front left perspective view of the stabilizer for mechanical devices of FIG. 1 in the first configuration.

FIG. 9 is a front view of the stabilizer for mechanical devices of FIG. 1 in the first configuration.

FIG. 10 is a rear view of the stabilizer for mechanical devices of FIG. 1 in the first configuration.

FIG. 11 is a right view of the stabilizer for mechanical devices of FIG. 1 in the first configuration.

FIG. 12 is a left view of the stabilizer for mechanical devices of FIG. 1 in the first configuration.

FIG. 13 is a top view of the stabilizer for mechanical devices of FIG. 1 in the first configuration.

FIG. 14 is a bottom view of the stabilizer for mechanical devices of FIG. 1 in the first configuration.

FIG. 15 is a front left perspective view of the stabilizer for mechanical devices of FIG. 1 in a second open configuration.

FIG. 16 is a front right perspective view of the stabilizer for mechanical devices of FIG. 1 in the second configuration.

(Continued)

FIG. 17 is a rear left perspective view of the stabilizer for mechanical devices of FIG. 1 in the second configuration. FIG. 18 is a rear right perspective view of the stabilizer for mechanical devices of FIG. 1 in the second configuration. FIG. 19 is a front view of the stabilizer for mechanical devices of FIG. 1 in the second configuration. FIG. 20 is a rear view of the stabilizer for mechanical devices of FIG. 1 in the second configuration. FIG. 21 is a right view of the stabilizer for mechanical devices of FIG. 1 in the second configuration. FIG. 22 is a left view of the stabilizer for mechanical devices of FIG. 1 in the second configuration. FIG. 23 is a top view of the stabilizer for mechanical devices of FIG. 1 in the second configuration. FIG. 24 is a bottom view of the stabilizer for mechanical devices of FIG. 1 in the second configuration. FIG. 25 is a top view of the stabilizer for mechanical devices of FIG. 1 in the first configuration with the environmental structure removed. FIG. 26 is a bottom view of the stabilizer for mechanical devices of FIG. 1 in the first configuration with the environmental structure removed. FIG. 27 is a top view of the stabilizer for mechanical devices of FIG. 1 in the second configuration with the environmental structure removed; and, FIG. 28 is a bottom view of the stabilizer for mechanical devices of FIG. 1 in the second configuration with the environmental structure removed.

The dashed lines in the drawings represent environmental structure that forms no part of the claimed design.
